UNITED STATES PATENT OFFICE.

ALBERT KESSLER, OF MITTWEIDA, GERMANY, ASSIGNOR TO THE CHORE-UTENSILS CORPORATION OF AMERICA, OF WEST ORANGE, NEW JERSEY, A CORPORATION OF NEW JERSEY.

SCOURING IMPLEMENT.

Application filed May 17, 1922. Serial No. 561,778.

To all whom it may concern:

Be it known that I, ALBERT KESSLER, a citizen of Germany, residing at Mittweida, Saxony, in Germany, have invented certain new and useful Improvements in Scouring Implements; and I do hereby declare the following to be a full, clear, and exact description of the invention, such as will enable others skilled in the art to which it appertains to make and use the same, reference being had to the accompanying drawings, and to characters of reference marked thereon, which form a part of this specification.

This invention relates, generally, to improvements in scouring implements; and the invention has reference, more particularly, to a novel construction of hand implement or device for cleansing and brightening surfaces which require the application of an abrasive action thereto, such, e. g., as metallic surfaces of various kinds, and such as cooking utensils and the like.

The invention has for its principal object to provide a strong, durable, efficient and sanitary implement or device for performing scouring operations, of such convenient shape and structure, that the same may be very easily and comfortably handled and manipulated, and which, at the same time, will produce a mild abrasive effect upon the surface to which it is applied in use.

The invention has for a further object to provide a scouring device made of metallic material, preferably in the form of flat and narrow ribbon-like strands, which are interwoven together, and then shaped to produce an elastic spongiform mass which is adapted to readily conform itself to the surface to which it is applied, and which, by reason of its shape and regularity of structure, presents no sharp ends or points likely to prick or irritate the hands of the user, and which furthermore, by reason of its spongy or porous structure readily permits the penetration and flow of water or other cleansing fluid therethrough, whereby it may be kept in a clean and sanitary condition.

Other objects of this invention, not at this time more particularly enumerated, will be clearly understood from the following detailed description of the same.

The invention is clearly illustrated in the accompanying drawings, in which:—

Figure 1 is a plan view of the preferred form of my novel scouring device, made according to and embodying the principles of this invention; Figure 2 is a detail transverse section of the same, and drawn on a somewhat enlarged scale; and Figure 3 is a diagrammatic view illustrating the preferred method of producing the device.

Similar characters of reference are employed in the above described views, to indicate corresponding parts.

According to the principles of this invention, my novel scouring device or implement comprises a knitted or woven metallic fabric rolled over upon itself or spirally wound to produce an elastic spongiform mass of cylindrical shape suitably secured against unwinding.

The metallic fabric is preferably constructed of a thin ribbon-like wire, made of a non-corrosive metal of a suitable degree of hardness, such, e. g., as copper. The fabric is produced by forming a series of rows of interlocked loops of said ribbon-like wire, until a desired area of the fabric is attained, whereupon the same is rolled or spirally wound upon itself to form the desired cylindrical shape, and then secured, to retain the shape, by suitably fastening the outer or free edge of the fabric to the cylindrical mass thus produced. The spirally wound convolutions of the fabric, thus arranged, form an elastic spongiform cylindrical mass, the loops of the outer layers of which present a multiplicity of sharp edges, whereby a desired scraping or abrading action is attained when the device is rubbed over the surface to be cleaned, and yet, owing to the rounded character of the projecting loops, all sharp points likely to penetrate or irritate the user's hand are eliminated.

Referring now to the accompanying drawings, I have shown therein the preferred form of scouring device or implement made according to and embodying the principles of this invention, which, as shown in Figure 1 consists of an annular body 1 substantially cylindrical or circular in cross-section. To produce this preferred form of my invention, I first construct a tubular or sleeve-

like member 2 made of the metallic fabric formed by rows of interlocked loops 3 of narrow ribbon-like wire (see Figure 3), whereupon I turn the lower edge of said 5 tubular or sleeve-like member 2 outwardly and upwardly upon itself (as indicated by the arrows *x* in said Figure 3), so that the same may be rolled up to produce the spirally wound body 4 as indicated by the 10 dotted representation thereof shown in said Figure 3, and as also shown more clearly in Figure 2, thus producing the annular cylindrical body 1 shown in Figure 1. The outer or free edge 5 of the fabric is preferably located at the inner side of said annular cylindrical body, and the same is secured against 15 unwinding or displacement by means of wire stitches 6 or other suitable fastening means for firmly attaching said edge 5 to the mass 20 of the body 1, as shown in Figure 2.

The annular cylindrical body 1 presents at its outer surface a multiplicity of projecting loop portions 7 which provide sharp scraping edges for producing the abrasive action desired of the device when rubbing the same against the surface to be cleaned; 25 said rounded projecting loops eliminating all sharp points adapted to penetrate or irritate the hand of the user. The novel 30 scouring device is more or less elastic, so that when pressed against a surface to be cleaned the same will conform thereto and effectively contact therewith, as e. g., when pressing the same into the corners or angles of a pot, 35 kettle or pan. As will be evident the mass of the device is porous or spongiform, that is the same is interspersed with interstices, so that water or other cleansing fluid may readily penetrate and flow therethrough. 40 when it is desired to clean the device after the same has been used, and consequently the same may be kept in a sanitary condition at all times.

The annular cylindrical shape which I 45 have found to be the most preferable form of my invention, not only provides a device of sufficient bulk to be strongly gripped and held in the hand when the same is being used, but its annular shape permits the same 50 to be easily and securely suspended from a peg, hook or similar support when not in use, always conveniently at hand, while at the same time it will, when so suspended, readily drain itself and dry out.

55 While the annular shape of my scouring device, shown in the drawings and above described, is preferable, I do not wish to limit myself entirely to such shape, since it will be clearly understood that the substance and 60 principles of my invention, so far as the production of a spongiform or porous mass formed of a metallic wire fabric is con-

cerned may be readily embodied in other shapes than said annular shape.

I claim:—

1. A scouring implement, comprising a tubular metallic fabric member spirally rolled upon itself in the direction of its length to provide an annular body forming an elastic spongiform mass. 65

2. A scouring implement, comprising a tubular metallic fabric member spirally rolled upon itself in the direction of its length to provide an annular body forming an elastic spongiform mass, and means for 70 securing the outer free edge of the fabric member to the rolled mass of said annular body.

3. A scouring implement, comprising a tubular metallic fabric member formed by 80 a series of rows of interlocked loops of narrow ribbon-like strands, said fabric member being spirally rolled upon itself in the direction of its length to provide an annular body forming an elastic spongiform mass. 85

4. A scouring implement, comprising a tubular metallic fabric member formed by 90 a series of rows of interlocked loops of narrow ribbon-like strands, said fabric member being spirally rolled upon itself in the direction of its length to provide an annular body forming an elastic spongiform mass, and means for securing the outer free edge of the fabric member to the rolled mass of 95 said annular body.

5. A scouring implement, comprising a tubular metallic fabric member formed by a series of rows of interlocked loops of narrow ribbon-like strands, said fabric member being spirally rolled upon itself in the direction of its length to provide an annular body forming an elastic spongiform mass, and a series of fastening stitches joining the outer free edge of the fabric member to the 100 rolled mass of said annular body. 105

6. A scouring implement, comprising a tubular metallic member formed by a series of rows of interlocked loops of narrow ribbon-like strands, said fabric member being spirally rolled upon itself in the direction 110 of its length to provide an annular body forming an elastic spongiform mass, and the outer layers of said rolled mass of said annular body being adapted to present a multiplicity of loop projections providing 115 sharp scraping edges.

In testimony, that I claim the invention set forth above I have hereunto set my hand this third day of January, 1923.

ALBERT KESSLER.
